UNITED STATES PATENT OFFICE.

JOHN B. EHRLICH, OF PORTLAND, OREGON.

FIREPLACE.

Application filed July 15, 1926. Serial No. 122,617.

This invention relates generally to heating appliances and particularly to a special form of fireplace construction.

The main object of this invention is to construct a special form of fireplace by means of which heat can be derived from fuel without the production of smoke or soot in which a large portion of the heat units ordinarily escape to the atmosphere or is deposited in the smoke flues and on the firewalls of the fireplaces.

The second object is to so construct the fireplace that the heated sidewalls thereof cause a circulation of air into the room being warmed and a portion of the air thus warmed is employed to obtain the complete combustion above referred to.

The third object is to construct the fireplace that it can readily be installed within the ordinary fireplace or placed against a plain wall and connected with the ordinary round smoke-flue opening such as are used with stoves and ranges.

The fourth object is to overcome one of the main objections to ordinary fireplaces namely the uneven heating of a room by causing it to circulate the air and maintain an even temperature at all points of the room under all ordinary conditions.

These, and other objects, will become more apparent from the specification following as illustrated in the accompanying drawings, in which:

Figure 1 is a front elevation of the fireplace showing one half broken away in vertical section along the line 1—1 in Figure 2. Figure 2 is a broken horizontal plan taken along the line 2—2 in Figure 1. Figure 3 is a vertical transverse section taken along the line 3—3 in Figure 1. Figure 4 is an enlarged detail of the firewall structure showing the air inlet openings between the imitation bricks. Figure 5 is a perspective view of the grate and ashflue door and damper with the operating mechanism. Figure 6 is a perspective view of a modified form of fireplace adapted to be set into the ordinary fireplace opening.

Similar numbers of reference refer to the same parts throughout the several views.

Referring in detail to the drawings, the form illustrated in Figures 1 to 3 inclusive is adapted to be placed against a plain wall 10 in which is a chimney 11 such as are in common use.

The fireplace itself has a base 12 in which

is mounted the grate 13, on its trunnions 14. A pushrod 15 is attached to the arm 16 and is used to rock the grate 13. Under the grate 13 is an ash chute 17 having a trap door 18 mounted on the pivots 19 and connected by the link 20 to the arm 16 of the grate 13, so that when the grate 13 is in its closed position, the trap door will be shut. Any rocking motion imparted to the grate 13 by the rod 15 will also rock the door 18 and allow the ashes to escape into the chute 17.

A damper 21 is placed on the chute 17 under the front of the grate 13. A pushrod 22 is employed to operate the damper 21. Air inlet openings 23 are formed on the under side of the base 12 through which air is drawn from the floor 24. A cover 25 is provided for the base 12. A curved guard 26 on the cover 25 prevents coals from getting out of the fireplace into the room. The fire wall 27 resembles brickwork but is made of metal. The open joints 29 between the steps or bricks are chamfered to facilitate molding.

Behind the wall 27 and spaced therefrom is a back 30 preferably lined with insulating material 30—A, and spaced from the wall 10 if desired. Side walls 31 are integral with the front 32, in the upper portion of which are formed the air outlet openings 33.

The outer edge 34 of the member 27 is downturned to assist in controlling the paths of the air and gas currents. The member 27 is provided with a flange 35 by means of which it joins the front 32.

In some cases a grille 36 is hinged or otherwise attached to the edge 34 and is lined with metal cloth as a protection against sparks.

At the top of the firewall 27 is attached the smoke duct 37 which is provided with a damper 38 and its flange 39 connects with the smoke flue 11. A chain 40 is employed to operate the damper 38. Any type of mantle 41 may be used.

In the modification shown in Figure 6 there is illustrated the ordinary fireplace 105 front 42 whose throat 43 is closed with a plate 44 adapted to receive the round smoke flue 45 of my fireplace. In this case the back 30 and side walls 31 are not required and the front 46 engages the front of the 110 bricks 42. The other elements are the same as in the first described form of the device.

When the existing fireplace is provided with a damper 47, then the damper 38 may also be omitted.

Either form of this fireplace is operated the same as follows: Fire is started on the grate 13 with the dampers 21 and 38 open. When the walls become heated, the dampers are gradually closed and heated air is supplied to the combustion through the openings 29.

Only as much air is drawn through the openings 29 as is actually required by the combustion. The remainder of the air passing upwardly through the air space enters the room through the openings 33.

It can be seen that by this construction the usual large labor item in fireplace construction is greatly reduced and fireplaces having undersized flues and wrongly constructed throats can be made to operate in a more efficient manner. No attempt is made at showing decorative elements since they do not enter into this invention.

I claim:

1. A fireplace having a hinged grate, a grate-holding base including a fire wall, an ash duct under said grate having a normally

closed door thereon, a link connecting said grate and door, and means for actuating said link in a manner to open said door when said grate is opened.

2. A fireplace having a hinged grate, a grate-holding base including a fire wall, an ash duct under said grate having a normally closed door thereon, a link connecting said grate and door, means for actuating said link in a manner to open said door when said grate is opened, and a damper for controlling the supply of air to the under side of said grate.

3. A fireplace having, in combination, a hinged grate, a grate supporting base, an ash duct positioned under said grate, an ash duct door on said duct, a link between said grate and door whereby said duct door will be operated in unison with said grate, means for actuating said grate and door consisting of a rod attached to said link, a fire wall around said grate, and outer walls enclosing said fire walls having openings therein whereupon heated air may escape from the outer walls into the room.

JOHN B. EHRLICH.
